ASH RECEPTACLE

John G. Hickman, Detroit, Mich., assignor to
Ternstedt Manufacturing Company, Detroit,
Mich., a corporation of Michigan

Application April 11, 1938, Serial No. 201,240

2 Claims. (CL 131—235)

This invention relates to ash receptacles and particularly to an ash receptacle which is adapted for use in an automotive vehicle.

In prior art it is known to equip an ash tray or some part pertinent thereto with a snuffer, and these snuffers have been somewhat troublesome in that they made no adequate disposition of the cigar or cigarette ashes which were deposited in the snuffer. At times the objectionable ashes were allowed to fall in the car, over the seats, and soil the seat covers as well as the clothing of the passengers. In the present invention the snuffer is placed on the cover on the inside so that when the cigarette or the cigar is snuffed the ashes will be retained in the snuffer, or allowed to fall into the receptacle. When the cover is closed, the snuffer part thereof will be substantially inverted and enable the ashes to fall into the receptacle.

20 On the drawing

Figure 1 is an inside view of the rear part of an automotive vehicle showing the invention applied.

Figure 2 is a perspective view of a composition ash receptacle showing the cover in open position and the snuffer exposed.

Figure 3 is a sectional view of the structure of Figure 2 showing the cover in closed or lowered position.

30 Figure 4 is a side view of the metal ash receptacle with parts broken away and shown in section better to illustrate the snuffer.

Figure 5 is a sectional detail on the line 5—5 of Figure 4.

35 Figure 6 is a combination of the metal receptacle of Figure 3 and the composite cover of Figure 2.

Figure 7 is a detailed view of the inside of the cover showing a modified form of snuffer.

40 On the drawing the numeral 2 indicates an automotive vehicle as a whole. The vehicle has the door 4, the door window 6, the floor 8, the rear quarter window 10, the rear deck window 12, the rear deck 14, the seat back 16, the seat bottom 18, and the arm rest 20. These parts are conventional and per se form no part of the invention.

45 The arm rest 20 is provided with an opening in which the ash receptacle 22 of the invention is positioned. The ash receptacle comprises the lower container 24 and the cover 26. In Figure 2, parts 24 and 26 are made of a composition material.

The cover has the handle part 28, by means of which the cover may be raised, and also the

ears 30 which project into the container 24 and are provided with trunnions 32 which project into the recesses 34 in the sides of the container 24. The trunnions have flats 36 and 38 which are adapted to be engaged by the sides of the U-shaped springs 40. The springs 40 are retained in the recesses 34 by means of the bent ends 42 which fit into the slots in the side of the recess 34. In the position of the cover shown in Figure 2, the spring 40 engages the flat 38, while in the position shown in Figure 3 the springs engage the flats 36. These springs will hold the cover in either of its extreme positions, when the springs are in engagement with either of the flats.

15 The inside of the cover 26 is provided with the integral snuffer 44. The snuffer itself comprises an extension on the cover, the extension having the conical recess 46 which is adapted to receive either a cigar or cigarette to be snuffed. In the 20 position shown in Figure 2, the snuffer is accessible, and after the cigar or cigarette has been snuffed, the ashes will be retained in the bottom of the recess 46. When the cover is closed to the position shown in Figure 3, the ashes will 25 fall from the recess into the container 24 due to the fact that the recess and the snuffer are now in substantially inverted position. The corners of the container 24 are provided with shoulders 48 to serve as abutments for the cover 26 in its 30 closed position.

In Figure 4 the container 24' is made of metal and has the flange 50 to strengthen the construction and to form an abutment which will retain the container 24' in the opening in the arm 35 rest 20.

The cover 26' is of metal and has the ears 30' through which pass the rivets 50 to form a hinge for the cover. A suitable anti-squeak washer 52 is positioned between the ears 30' and the inside 40 of the receptacle 24'.

A snuffer 44' is of substantially the same shape as the snuffer 44 shown in Figure 2 and is provided with the recess 46' in which the end of the cigarette or cigar may be snuffed. The 45 snuffer is provided with the downturned outer reinforcing flange 54 to strengthen the construction and at the side adjacent the cover 26' the flange 54 is provided with an ear 56 which has an opening through which there passes the 50 screw 58, which is threaded into the handle 60 on the outside of the cover and retains the snuffer in place.

In Figure 6 there is shown the combination of the metal container 24' of Figure 4 and the 55

cover 26" of Figure 2. The distinction between the cover in Figure 6 and the cover in Figure 2 resides in the fact that there are no trunnions in Figure 6 corresponding to the trunnions 32 in Figures 2 and 3. The ears 30" in Figure 6 have an opening through which there passes the rivet or pin 50' to hinge the cover. A bent-in part 61 is provided to limit the inward movement of the cover 26".

10 In Figure 7 the cover 26" has the handle 28 and a snuffer 44". The snuffer 44" is formed as an extension on the inside of the cover and has the recess 46". The recess is open at the side facing the receptacle when the cover is in closed position, and a slot 62 is provided therein. The slot 62 extends a little over half way into the snuffer and the sides thereof are either tapered or rounded with the wider part at the outside of the snuffer. The smoker may snuff the cigarette, either by placing it directly in the recess 46" or he may press the lighted cigarette end from the outside into the slot, to cause the sides of the slot 62 to bite over the lighted end to cause the ignited end to be snuffed.

15 20 25 In the species of Figures 4, 6, and 7, the operation is the same as that described in connection with the species of Figures 2 and 3. In open

position of the cover the cigarette or cigar may be snuffed by pressing the end thereof in a snuffer 44" or 44" and any ashes which will be retained therein will drop into the container 24 or 24' when the cover is lowered to the position 5 shown in Figure 3.

I claim:

1. In an ash receptacle for an automotive vehicle, a cover swingably connected to the receptacle, a snuffer on the inside of the cover, said snuffer having a slot in its bottom to enable the insertion and snuffing of a cigarette, said snuffer opening in a downward direction to discharge the ashes therefrom when the cover is in closed position, and being in an upwardly directed position when the cover is open.

2. In an ash receptacle for automotive vehicles, a cover swingably connected to the receptacle, a snuffer on the inside of the cover, said snuffer having a slot with diverging sides in its bottom to enable the insertion and snuffing of a cigarette, said snuffer opening in a downward direction to discharge ashes therefrom when the cover is in closed position and being in an upwardly directed position when the cover is open.

JOHN G. HICKMAN.
